UNITED STATES PATENT OFFICE.

JOHN J. LYTH, OF VALLEYFIELD, QUEBEC, CANADA.

FUSIBLE LINK.

Application filed May 19, 1920. Serial No. 382,531.

To all whom it may concern:

Be it known that I, JOHN J. LYTH, a subject of the King of Great Britain, and resident of the city of Valleyfield, in the Province of Quebec and Dominion of Canada, have invented certain new and useful Improvements in Fusible Links, of which the following is a full, clear, and exact description.

19 This invention relates to improvements in fusible links for use in connection with fire protection sprinkler systems and the like, and the object of the invention is to provide a link which may be easily and cheaply 20 manufactured and which will be quick and positive in operation.

The invention resides briefly in providing a pair of plates each having an abutment or seat thereon and a rocker located between the 25 seats and holding the plates against relative movement in a predetermined direction.

In the drawings which illustrate the invention:—

Fig. 1 is a plan view of a link according 25 to this invention.

Fig. 2 is a side elevation of the link.

Figs. 3, 4 and 5 are plan views illustrating slight modifications of the link shown in Figure 1.

30 Referring more particularly to the drawings, 11 and 12 designate a pair of plates, which for convenience may be referred to as back and front plates respectively. These plates overlap and are each provided at one 35 end with an aperture 13 for connection with a sprinkler head or other apparatus. The back plate 11 is bent rearwardly at a transverse line toward the end remote from the aperture 13, thus forming a sloping portion 40

14 and is then bent forwardly at substantially right angles to the part 14 to form a transverse seat 15 located in rear of the plate 12. It will be observed that the seat 15 is on the front surface of the back plate 11. The 45

front surface of the plate 12 is provided with a bent-up portion 16 forming a seat at the front of the plate. A strut, rocker or key 17 is rockably mounted on the seat 16 and passes to the back of the plate 12 and bears 50 against the seat 15 of the plate 11. When the link is loaded in the predetermined direction the plates 11 and 12 tend to slide past one another. This sliding movement is resisted by the strut or key 17 which is in compression 55 between the plate seats but owing to the

inclination given the key by reason of its passage from the front to the back of the plate 12, it will rock on its seats when the link releases under tension and force the plates apart laterally. In making up the 60 links the plates and the strut or key are connected together by solder fusible at a low temperature in the well known manner, with the result that the parts are held against movement at ordinary temperatures but will, 65 upon softening of the solder at increased temperature, move as above described.

In the form shown in Figure 1 the plate 12 is, as a whole, narrower than the plate 11 and the strut 17 is a U-shaped wire lying at 70

its central or root portion across the plate 12. The arms of this strut pass one on each side of the plate into engagement with the seat of the back plate 11. The inclination given 75

the portion 14 of the back plate is for the purpose of accommodating the inclined strut as will be clearly seen in Figure 2. The seat 16, which is turned-up from the plate 12, may be formed in a variety of ways of which one 80

is shown in Figures 1 and 2. The lower portion of the plate 12 is made of substantially the same width as the plate 11 and, therefore, projects beyond the edges in the remainder of the plate length. These projections 85

are turned upwardly to form a seat for the strut. It will be noted that, as only the thickness of the plate is presented as a seat, there are two lugs in order to provide stable support for the strut. While these 90

lugs have been formed by turning metal at the edges upwardly or toward the centre line 95

of the plate, it will be understood that the same result may be produced by starting on a cut in the centre line of the plate and turning the metal upwardly and away from the 100

centre as shown in Figure 5. It will also be understood that a seat may be provided by turning up a single tongue of metal in the transverse direction of the plate as shown in 105

Figures 3 and 4. Apart from the method of producing the seat 16 the forms shown in Figures 3 and 4 differ from the form shown in Figure 1 in the provision for the passage of the strut from the front to the back of 110

the front plate. In Figure 1 the strut passes outside the edges of the plate 12. In Figure 3 the strut is of the same U-shape but narrower and slots 18 are provided close to the edges of the plate 12^a for the passage of these arms. In Figure 4 a single slot 18^a is pro- 110

vided in the centre line of the plate 12^b and the strut, while still of U-shape, is closed-up to pass through a single slot. In order to prevent rocking of the narrower strut its extremities are turned outwardly as shown at 19 and may rest upon the seat 16 or upon the seat 15 as may be found most expedient. Obviously the strut 17^a shown in Figure 4 may be used in the inverted position shown in connection with seats 16 formed as in Figures 1 or 5. In all forms the back plate 11 is the same.

Having thus described my invention, what I claim is:

15. 1. A fusible link comprising a pair of plates in slidable engagement, said plates having seats on the front faces thereof, and a strut in compression between said seats.
20. 2. In a fusible link, a pair of plates in slid-
able engagement, seats on the front faces of
said plates, and a strut in compression be-
tween said seats extending through the
thickness of one of the plates.
25. 3. A fusible link comprising a pair of
plates in slidable engagement, a seat on the
front surface of each plate, and a U-shaped
strut in compression between said seats.
30. 4. A fusible link comprising a pair of
plates in slidable engagement, one of said
plates being turned away from the other
plate and then sharply toward the other
plate to form a seat on the front face thereof,
a lug on the front face of the other plate

forming a second seat, and a link in com-
pression between said seats.

35. 5. A fusible link comprising a pair of
plates in slidable engagement and each aper-
tured adjacent one end, a seat provided on
the front face of each plate toward the end
opposite the aperture, and a strut in com-
pression between said seats.

40. 6. A fusible link comprising a pair of
plates in slidable engagement and each aper-
tured toward one end, a seat forming lugs
turned up on the front surfaces of the plates
45 toward the ends thereof remote from the
apertures and a strut in compression between
said lugs.

50. 7. A fusible link comprising a pair of
plates in slidable engagement, seats pro-
jecting from corresponding surfaces of said
plates, one of the plates being formed for
the passage of a link from front to back
thereof, and a strut in compression between
55 the seats passing from front to back of said
plate.

8. A fusible link comprising a front plate
and a back plate, the front plate being cut
away to expose part of the back plate and
to give passage to a strut, seats formed on
the front surfaces of the plates and a strut
held in compression between said seats.

In witness whereof, I have hereunto set
my hand.

JOHN J. LYTH.
